A. F. ^{ATTORNEY}

UNITED STATES PATENT OFFICE

GUSTAVE H. JANTZ, OF WYOMING, OHIO

SAFETY RELEASE MECHANISM FOR WRINGERS

Application filed September 27, 1929. Serial No. 395,600.

It is the object of my invention to provide novel quick releasing mechanism whereby pressure between the rolls is instantly released to avoid accident or injury to the user, or when it is desirable for any other reason to instantly relieve or release pressure between the rolls.

It is the object of my invention further to provide novel quick releasing mechanism at an end of the machine; and, further, to provide novel, simple and durable mechanism of few parts which are readily assembled and of compact arrangement at the end of the machine arranged to be pressed for quick release of pressure between the wringer rolls.

It is the object of my invention further to provide novel latching means for normally holding the top-bar in operative position and readily releasing the same, and to provide novel latching means arranged for release by manual manipulation of releasing means at the end of the machine and releasing mechanism at the top-bar selectively employable for releasing pressure between the wringer rolls.

The invention will be further readily understood from the following description and claims, and from the drawings, in which latter:

Fig. 1 is a front elevation of my improved device.

Fig. 2 is an end elevation of the same.

Fig. 3 is a vertical longitudinal section of the same, taken on the line 3—3 of Fig. 2.

Fig. 4 is an enlarged longitudinal vertical sectional detail view of the same, taken on the same section line.

Fig. 5 is a sectional detail view showing the hanging of the upper roll, taken in the plane of the line 5—5 of Fig. 3.

Fig. 6 is a horizontal section of my improved device, taken in the plane of the irregular line 6—6 of Fig. 3.

Fig. 7 is a vertical longitudinal section of a modification of my improved device, taken on the line 7—7 of Fig. 8, and partly broken away.

Fig. 8 is an end view of the same; and,

Fig. 9 is an enlarged longitudinal sectional detail view of the same, taken on the line 7—7 of Fig. 8.

My invention is an additional species of the invention shown, described and claimed in my copending application for patent on improvement in safety release mechanism for wringers, filed in the United States Patent Office September 30, 1929, as Serial No. 394,018.

The frame of the machine comprises end posts 11, 12, which are preferably hollow and substantially square in cross-section for providing upright channels 13, 14, in said posts. A lower connecting bar 15 has its respective ends rigidly secured to the lower ends of the respective posts. These parts may be of metal and may be formed up out of sheet metal.

Lower bearing blocks 17 are suitably supported in the upright channels of the end posts and form stationarily positioned bearings for the respective ends of a shaft 18 of the lower roll 19. This shaft has a formation 20 at one end thereof with which a suitable driving mechanism, which may be manual or power, has suitable connection for rotating the lower roll.

The upper roll 21 has a shaft 22, the respective end journals of which are received in bearing holes of bearing blocks 23 received in the upright channels of the end posts. The rolls are shown provided with traction sections 24 for aiding in rotating the upper roll by means of the driven lower roll.

The upper bearings are provided with bails 28 received over the respective ends of a leaf-spring 29. These bails may be of wire and have depending portions 30, the lower ends of which have inturned pivoting ends 31 received in apertures in the inner walls of grooves 32 at the respective ends of said bearings.

The spring is shown somewhat bowed, having a higher middle portion and lower end portions. The end portions of the spring rest on the upper faces of the upper bearings and are provided with holding means, for instance grooves 33, for receiving the upper stretches of the bails 28.

The frame of the machine comprises a top-bar 35 which is shown of inverted channel form having a top wall 36, side walls 37 and end walls 38, 39, forming an elongated down-

wardly presented pocket 40 in said top-bar.

The top-bar is provided at approximately its middle with a bearing 41 suitably secured thereto. A rocker-sleeve 45 is journaled in the bearing 41. The lower end of this rocker-sleeve is formed as a cam 46, provided with a cam-lobe 47, there being preferably a pair of these cam-lobes. The upper end of the sleeve has handle-arms 51 extending therefrom preferably normally lengthwise of the top-bar. There may be one or a pair of these handle-arms. The handle-arm is provided with a hub 52 which is secured to the sleeve, as by a pin 53, so as to rotate the sleeve therewith.

10 A screw-rod 55 has threaded connection in a threaded portion 56 of the bore of the sleeve, the lower end of the screw-rod preferably having journal connection in a bearing portion 57 of said sleeve.

15 The lower end of the screw-rod 55 is shown of ball form, as at 58, received in the socket of a socket-piece 59, the wall of the socket being pressed about the ball-portion of the rod for forming swivel connection therewith. The socket-piece is part of a saddle 60 about the middle portion of the spring. The saddle 60 is secured to the spring. The handle-arms 51 are preferably up-turned, as shown 20 at 61, for raising the outer ends of the handle-bars above the top-bar 35, so that the hand of the operator has free movement for operating said handle-arms without interference with the top-bar.

25 The upper end of the screw-rod 55 is provided with a handle 62, shown as a wing handle, suitably secured to the rod, as by a pin 63.

30 Referring to Figs. 1 to 6 inclusive, there is an upright lever 68 at the end of the machine. This lever is pivoted intermediate of its ends to the upright post 11, as by providing the lever with a bearing 69 and providing a lug-plate 70 having lugs 71 thereon, a pivot-pin 72 being received through the bearing and holes in said lugs. The lug-plate is suitably fixed, as by welding, to the end wall of the end-post 11. A stop 73 is on the lever and contacts the outer lateral wall of the post 11 for positioning said lever when the top-bar is removed.

35 The lever is provided with a latch 74 having an upper inclined face 75. The latch is received in an opening 76 in the end wall 38 of the top-bar. The lower wall 77 of said opening forms a keeper complementary to the latch for holding one end of the top-bar in down position. This latch is at the upper portion of the lever. The lever is provided with an upward extension 78 above the latch, the upper end of this upward extension being out-turned, as shown at 79, for providing an upper slanting face for the lever for aiding in assembling the top-bar on the posts.

The lower end of the lever is provided with

a pressure portion 81 upon which the operator may manually press for swinging the lever on its pivot and releasing the latch. This pressure portion is shown as a knob which preferably extends outwardly laterally from the lever and is rigid therewith and is provided with a hollow 82 opening toward the post.

40 A spring acts between the post and the lever for normally engaging the latch. Thus a spring 83 has its outer end received in the hollow 82, the inner end projecting toward the end post, there being preferably a cup 84, in which the inner end of the spring is received, the cup being interposed between the lever and the end-post. The open end of the cup is presented outwardly and the outer portion of the cup is preferably received in the hollow or socket 82 and has endwise movement therein.

45 At the other end of the machine there is preferably a releasable connection between the upright post at said end and the other end of the top-bar. This is accomplished by providing the outer end wall of said other upright post with a pin 85 preferably rigidly secured to said outer end wall, as by upsetting the same therein. The complementary end wall 39 of the top-bar is provided with a hole 86 complementary to said pin. The pin is preferably short so that ready release of the top-bar at said end may be had by moving said end wall outwardly with relation to said end post, said movement being preferably a tipping movement effected in the release of the top-bar.

50 The end wall 38 of the top-bar is provided with a hole 87 through which the outer end of an endwise movable rod 88 is arranged to project and to be urged outwardly by the cam 46 for moving the upper end of the lever 68 outwardly and thereby releasing the latch 74. This rod forms a tripper-rod for the latch. Release of the latch may also be effected by the operator by manually pushing upon the knob 81 for moving the upright lever on its pivot and moving the lower end of the lever toward the post 11, in a direction opposite to the direction of movement of the tripper-rod 88 when releasing said latch. As soon as such release takes place, whether by operation of the tripper-rod 88 by means of the handle-arm 51, or by inward pushing upon the pressure portion or knob 81, upward tilting movement of the top-bar is caused.

55 A spring 91, shown as a spiral spring, is received about the tripper-rod 88. The inner end of said spring is resisted by a washer 92 held to said rod by a pin 93 at one end of said spring, the other end of said spring being resisted for normally moving said tripper-rod inwardly toward the cam 46. The outward movement of said tripper-rod by either lobe of the cam causes release of the latch 74.

The tripper-rod slides endwise in bearings 94 in depending flanges 95 of a yoke 96 suitably secured to the upper wall of the top-bar.

Endwise movement of the tripper-rod 5 causes compression of the spring 91, the outer end of the tripper-rod cooperating with the upward extension 78 of the upright lever 68.

The upright lever 68 acts upon said tripper-rod and as soon as the latch is released, the 10 tripper-rod moves upwardly along said upward extension, and a reactive lengthwise movement of the top-bar toward the opposite end of the machine takes place for aiding in release of the releasable connection at the 15 other end of the machine, namely, the release of the wall of the hole 86 from the pin 85, whereby the top-bar is completely separated from the stationary part of the machine.

Such movement is also aided by the upward 20 force applied by the spring 29, and the swivel connection between said spring and the screw-rod, which permits ready tilting movement of the top-bar and aids in ready release of the releasable connection at the other 25 end of the top-bar.

Pressure between the rolls is thus completely released at both ends and throughout 30 the length of the rolls and the reactive movement of the spring 29 causes forceful upward movement of the top-bar, carrying the spring 29 with it, and also raising the bearings for the upper roll by the connection of the bails 28 thereof with the respective ends 35 of the spring 29. Complete release of pressure and spacing between the rolls takes place so that the fingers or hand of the operator and undue thickness of goods or other article or part, for instance clothing or hair of the 40 operator, may be withdrawn from between the rolls without injury.

Movement of the releasing cam is effected in either direction at either end and from either side of the machine, and the handle- 45 arms extend freely above the top-bar so that the same are free for ready grasping or pushing or pulling by the operator.

I have in Figs. 7, 8 and 9 shown a modification of my improved device in which the 50 latch and keeper are transferred respectively to the top-bar 35 and the upright lever 68. Similar parts of the latching means are designated by similar reference numerals with the exponent prime (').

In this modification the end wall 38' of 55 the top-bar has a lug 74' projecting endwise therefrom, the lug preferably having a lower sloping end face 75'. This lug may be struck up from the metal of the end wall or it may 60 be in the form of a pin which is fixed to the end wall. The upright lever 68' is provided with an opening 76' in which the lug is received, the upper wall of the lug bearing 65 upon the upper wall of the opening for latching the top-bar in place. The upper end of

the upright lever is provided with an outward curve 79' similar to the outward curve 79 and for a similar purpose. A stop 73' is on the lever.

In assembling my improved device, the 70 upper roll 21 is mounted in its bearings 23, the bails 28 of said bearings being received about the ends of the spring 29 and seated in the grooves 33 therein. The bearings are placed in the channels of the upright posts, 75 the upper roll resting upon the lower roll. The screw-rod 55 is reversely rotated for providing relief of pressure between the top-bar and the spring and permitting ready seating of the top-bar upon the end upright posts. 80

The top-bar is placed upon the end upright posts and tilted for placing the wall of the hole 86 in the end wall 39 about the pin 85. This causes the lower edge of the other end of the top-bar to be received about the upper 85 end of the other upright post, the lower edge of the end wall 38 of the top-bar resting upon the upper outwardly inclined wall of the upright lever. A sharp blow of the fist upon the upper face of the end of the top-bar adjacent the upright lever causes seating between the latch and the keeper at said end of the top-bar.

This relation of the parts when assembled is shown in the drawings. The lobes of the 95 cam 46 extend at right angles to the handle-arms 51, the handle-arms extending lengthwise of the top-bar. The inner end of the tripper-rod preferably contacts the low point of the cam for aiding in maintaining the cam 100 and the handle-arms in their desired neutral or inactive relations.

When now it is desired to release the top-bar, for instance, for avoiding accident, either handle-arm is pushed forwardly or pulled rearwardly from either side of the wringer, whereby one face of one of the cams rides upon the inner end of the tripper-rod for causing the tripper-rod to move axially outward and press upon the lever 68 for releasing the latch 74. 110

Upon release of the latch, either by operation of the handle-arm for operating the tripper-rod or by manual pressing upon the pressure knob 81, the top-bar springs upwardly, due to release of pressure between the rolls 21 and 19, caused by release of pressure of the screw-rod 55 upon the middle portion 115 of the spring 29. The release of the latch causes a tilting movement of the top-bar by the action of the middle portion of the spring 29 upon the screw-rod 55 in the middle portion of the top-bar for tilting the top-bar, due to momentary resistance of the pin 85 upon the other end of the top-bar. 120

The tilting movement of the top-bar and the reaction of the quick forceful release thereof, causes disengagement between the end wall 39 of the top-bar and the pin 85, for releasing the top-bar entirely and permitting 130

upward movement of the entire top-bar. This upward movement is a quick forceful movement which ordinarily would cause the top-bar to fly upwardly away from the balance of the wringer frame.

- 5 In order to employ this inertia of motion of the top-bar for further relief of pressure between the wringer-rolls, the bearings of the upper wringer-roll are hung upon the spring 29 which is in turn swiveled to the screw-rod 55, threaded in the rocker-sleeve 45 of the cam 46, rotating in the top-bar, whereby the spring, the bearings and the upper roll are moved upwardly for separation between the upper roll and the lower roll.

10 15 My improved device is simple in construction, comprises few parts readily assembled, and is extremely effective in affording quick and instant relief of pressure between the wringer rolls.

20 25 I do not herein broadly claim the releasing mechanism connecting with the top-bar, herein shown and described, having shown, described and claimed the same and a species thereof in my said copending application.

Having thus fully described my invention, what I claim as new, and desire to secure by Letters Patent, is:

1. In a device of the character described, the combination of a frame comprising a stationary part including end upright posts, a releasable top-bar between the upper ends of said posts, complemental wringer rolls mounted in said frame, separation between said rolls being normally resisted by said top-bar, and latching means between said stationary part and said top-bar comprising an upright lever having pivot connection with one of said upright posts, said upright lever located outside said last-named upright post and said top-bar and having releasable latch connection with said top-bar, said pivot connection being intermediate of the length of said lever, the lower end of said lever provided with a pressure portion, and spring means having operative connection with said lever normally urging engagement in said latch connection.

2. In a device of the character described, the combination of a frame comprising end upright posts, a top-bar between the upper ends of said upright posts, said top-bar having a top wall, depending side walls and depending end walls forming a hollow structure the hollow of which is presented downwardly as a canopy, said canopy protectingly located above the upper ends of said upright posts, which latter are respectively received in the respective ends of said hollow, a releasable connection between one of said upright posts and one of said end walls, and latching means between the other of said upright posts and the other of said end walls comprising an upright lever pivoted intermediate of its ends to said last-named upright post and having releasable latch connection

nection at its upper end with said last-named end wall, said last-named end wall located between said last-named upright post and said upper end, and the lower end of said lever provided with a pressure portion for 70 releasing said latch connection.

3. In a device of the character described, the combination of a frame comprising a stationary part including end upright posts and a releasable top-bar between the upper ends 75 of said posts, complemental wringer rolls mounted in said frame, separation between said rolls being normally resisted by said top-bar, and latching means between said stationary part and said top-bar comprising 80 an upright lever having pivot connection with one of said upright posts, said upright lever located outside said last-named upright post and said top-bar and having releasable latch connection with said top-bar, said pivot connection being intermediate of the length of said lever, the lower end of said lever provided with a hollow pressure knob, and a spring in the hollow of said knob between said knob and said upright post arranged for 85 causing normal engagement in said latch connection.

4. In a device of the character described, the combination of a frame comprising end upright posts, a top bar between the upper 95 ends of said upright posts, said top bar having a top wall, side walls and end walls forming a hollow structure the hollow of which is presented downwardly, the upper ends of said upright posts respectively received in 100 the respective ends of said hollow, a releasable connection between one of said upright posts and one of said end walls, and latching means between the other of said upright posts and the other of said end walls comprising 105 an upright lever pivoted intermediate of its ends to said last-named upright post and having releasable latch connection at its upper end with said last-named end wall, the lower end of said lever provided 110 with a hollow pressure knob the hollow of which is presented inwardly, a cup in the hollow of said pressure knob having its open end presented outwardly, and a spring in 115 said hollow and in said cup, the inner end of said cup positioned by said post, and arranged for normally causing engagement in said latch connection.

5. In a device of the character described, the combination of a frame comprising end 120 upright posts, a top bar between the upper ends of said upright posts, said top bar having a top wall, side walls and end walls forming a hollow structure the hollow of which is presented downwardly, the upper ends of 125 said upright posts respectively received in the respective ends of said hollow, releasable connecting means between one of said end upright posts and one of said end walls, an upright lever having pivot connection inter- 130

- mediate of its ends with the other of said end upright posts, a latch connection between the upper end of said upright lever and the other of said end walls, a tripper-rod in said 5 top-bar, manual means on said top-bar for operating said tripper-rod, said tripper-rod having operative connection with said latch connection above said pivot connection for releasing said latch connection, and a pressure 10 knob at the lower end of said upright lever below said pivot connection, and arranged for release of said latch connection by operation of said tripper-rod and of said pressure knob in opposite directions.
- 15 6. In a device of the character described, the combination of a frame comprising a stationary part including end upright posts, a top-bar between the upper ends of said upright posts, said top-bar having a top wall, 20 depending side walls and depending end walls forming a hollow structure as a canopy, the hollow of which is presented downwardly, said canopy protectingly located above the upper ends of said upright posts, 25 which latter are respectively received in the respective ends of said hollow, an upwardly extending latch having connection with said stationary frame part below said top-bar, and one of said end walls of said top-bar received 30 between said latch and said upright post proximate thereto, said last-named end wall provided with a cooperating part cooperating with said latch, and a manual striker-part arranged for operative connection 35 with said latch for releasing said latch and whereby movement of said last-named end wall is permitted from between said latch and said upright post proximate thereto.
- 40 7. In a device of the character described, the combination of a frame comprising a stationary part including end upright posts, a top-bar between the upper ends of said upright posts, said top-bar having a top wall, 45 depending side walls and depending end walls forming a hollow structure as a canopy the hollow of which is presented downwardly, the upper ends of said upright posts respectively protectingly received under 50 said canopy in the respective ends of said hollow, complemental wringer rolls mounted in said frame under said canopy, separation between said rolls being normally resisted by said top-bar, a latch between said stationary frame part and one of said end walls of 55 said top-bar, said last-named end wall received between said latch and said upright post proximate thereto, said last-named end wall provided with a cooperating part operating 60 with said latch, and a manual striker-part for releasing said latch.
8. In a device of the character described, the combination of a frame comprising a stationary part including end upright posts, 65 a top-bar between the upper ends of said up-
- right posts, said top-bar having a top wall, depending side walls and depending end walls forming a hollow structure as a canopy the hollow of which is presented downwardly, the upper ends of said upright posts 70 protectingly received under said canopy respectively in the respective ends of said hollow, complemental wringer rolls mounted in said frame under said canopy, separation between said rolls being normally resisted by said top-bar, endwise releasable connecting means between one of said upright posts and one of said end walls, and a latch between the other of said upright posts and the other of said end walls, said other of said end walls received between said latch and said other of said upright posts, said last-named end wall provided with a cooperating part cooperating with said latch, and a manual striker-part for releasing said latch.
- In testimony whereof, I have hereunto signed my name.
